DEAN S. MORROW, OF EUGENE, OREGON

REMOTE CONTROL MEANS FOR CRANES

Application filed July 11, 1928. Serial No. 291,817.

This invention relates to improvements in remote control means for cranes and the like apparatus.

The principal object of this invention is to provide means whereby a crane, either a toy crane or a hoist crane may be controlled from a remote point in such a manner that all of the functions of the crane may be executed from the remote point.

10 A further object is to produce a device which is simple and therefore one which may be easily operated.

A still further object is to produce a device of this character without departing 15 from the customary practice in the construction of the crane.

Other objects and advantages will be apparent during the course of the following description.

20 In the accompanying drawings forming a part of this specification and in which like numerals are employed to designate like parts throughout the same.

Figure 1 is a side elevation partly broken 25 away showing my crane together with its carriage.

Figure 2 is a top plan view of Figure 1 and partly broken away in order to disclose the mechanism thereof,

30 Figure 3 is a fragmentary detail view showing the manner in which a plurality of contacts engage conductor rails,

Figure 4 is a fragmentary detail view showing the mechanism for moving the carriage from point to point,

35 Figure 5 is a cross sectional view taken on the line 5—5 of Figure 1, and

Figure 6 is a cross sectional view taken on the line 6—6 of Figure 1.

40 This invention is primarily designed for use with cranes commonly termed toy cranes which operate over a miniature track. Cranes of this character have heretofore been made, these cranes however, must be manually operated by the person using the

45 same after the crane has been placed upon the track at any predetermined point.

Applicant has therefore devised means whereby the crane may be moved from point to point through electrical means con-

trolled from a remote point, and further applicant has provided means whereby when the crane has reached a predetermined point the various movements of the crane may be executed also from the remote point.

It is of course obvious that the construction here shown if made upon a large scale could be readily employed, in the handling of large sized cranes commonly employed in handling of heavy material, with the result that a single operator could, from a tower, control the movement of a crane about a yard, handling various commodities and delivering these commodities to remote points.

In the accompanying drawings wherein for the purpose of illustration is shown a preferred embodiment of my invention, the numerals 5 and 6 refer to ordinary rails upon which the wheels 7 of the carriage roll. This carriage is designated as a whole by the numeral 8. Suspended beneath the carriage as by bearings 9 and 11 is a shaft 12, having a gear 13 at each end thereof. These gears mesh with gears 14 mounted upon the axle 70 of the wheels 7. It is of course obvious that the gear 14 at one end of the carriage is mounted upon the right hand wheel, while the gear at the opposite end of the carriage must be mounted upon the left hand wheel. 75

The shaft 12 carries a key 16 which slidably engages a collar 17 having gear faces 18 and 19. A slot is shown at 21, which slot is engaged by a yoke 22 pivoted as at 23 to the underside of the carriage 8. This 80 yoke carries an armature 24 which is in line with the poles of electromagnets 26 and 27. These electromagnets are each grounded as at 28 and 29 respectively. The electromagnet 26 is connected by a wire 31 to a contact 32, which engages a conductor rail 33 (see Figure 3). The electromagnet 27 is connected by a wire 34 to a contact 36 which engages a conductor rail 37.

A vertically disposed shaft 38 is suitably 95 journaled in the carriage 8 and has a gear 39 secured to its lower end, which gear is in alignment with the gears 18 and 19 and is adapted to be engaged by them as will be later seen. Mounted above the carriage 100

8 is a turn table gear 41. This gear is centrally disposed about the shaft 38 and serves to support the crane platform 42 as by rollers 43. The crane platform supports a super-structure designated as a whole by the numeral 44. In order to maintain the crane platform against vertical movement with respect to the gear 41, I provide a collar 46 which is preferably made integral with the gear 41 and is provided with an annular recess 47 which recess is engaged by the ends of retaining bolts 48 carried on a depending collar 49 which is secured to the crane platform 42. This construction permits rotary movement of the crane platform with respect to the carriage 8, but will not permit vertical movement with respect to each other. This construction is best shown in Figure 5.

By now referring to Figure 6, it will be noted that a tubular member 51 carries a plurality of rings 52 which rings are engaged by contact fingers 53 carried upon an upright 54. This tubular member 51 extends downwardly through the carriage 8. This permits the wires 56, 57, 58, 59, 61 and 62 to pass downwardly therethrough and outwardly as shown in Figure 1, which wires are in turn connected to the contacts 63, 64, 66, 67, 68 and 69 respectively. These contacts engage conductor rails 71, 72, 73, 74, 76 and 77 respectively. It is of course understood that each of these wires is connected to one of the rings 52.

A motor is shown at 78, which motor 35 drives a shaft 79 having a worm 81 secured thereto. This worm engages a worm gear 82 carried upon a cross shaft 83, which cross shaft carries a bevel gear 84 at one end which engages a bevel gear 86 carried upon 40 the upper end of the shaft 38. A bevel gear 87 is carried upon the opposite end of the shaft and is adapted to lie between bevel gears 88 and 89, while centrally disposed 45 on the shaft 83 is a gear 91 which meshes with a gear 92 carried upon a shaft 93. This gear 92 has a cone clutch 94 which engages an internal cone upon the brake drum 96. This brake drum is secured to a hoisting drum 97 which drum may be shifted 50 upon its shaft through the medium of a yoke 98 carried upon a pivoted lever 99. The end of this pivoted lever carries an armature 101 which is in alignment with 55 an electromagnet 102 mounted upon the crane platform 42, one side of which magnet is grounded while the opposite side is connected by wire 103 to contact finger 104. A lever 106 is pivoted to the platform as shown at 107, which lever has an arm 108 60 in engagement with an arm 109 of a lever 111 and pivoted as at 112. A spring 113 normally keeps the lever 111 in position shown in Figure 1.

It will be noted that this lever under- 65 lies an electromagnet 114 one side of which

is grounded, while the opposite side is connected by a wire 116 to contact finger 53. The lever 111 has an arm 117 one end of which is secured to a friction brake 118 carried upon the brake drum 96.

The motor 78 has one side grounded, while the opposite side is connected by a wire 119 to the contact finger 121. The remaining contact fingers shown but not numbered are connected to their respective electro-magnets, connection of which has been omitted in order to clarify the drawing. A hoisting cable is shown at 122, which hoisting cable needs no further description other than to say it is reaved over the crane arm 123.

Referring now to Figure 4 it will be noted that the gears 88 and 89 are carried upon a vertically disposed shaft 124, which shaft has a gear 126 at its lower end, which gear meshes with the turn-table gear 41 and is of a greater width than gear 41 which permits vertical movement of one gear with respect to the other without the gears getting out of mesh. A yoke 127 is carried upon a pivoted lever 128 and has a counter weight 129, which lever is pivoted as at 131. A downwardly extending arm 132 carries an armature 133, which armature is in alignment with the poles of electromagnets 134 and 136. These magnets are each grounded on one side and have their opposite sides connected as by wires 137 and 138 respectively to their proper contact fingers.

The operation of my crane is as follows:

Assuming that the same has been placed on the track as shown in Figure 3, so that the various contact arms engage the contact rails, and assuming that the operator desires to move the entire crane and carriage, the proper button is pressed so as to complete the circuit to the motor 78. This circuit may be kept closed at all times if desired. The operator next pushes the button which controls the electromagnet 27. This causes the armature 24 to move the yoke 22 and consequently the gear 19 into engagement with the gear 39 which is carried upon the constantly rotating shaft 38, this shaft being driven through its connection to the motor 78. As long as the electromagnet is energized the crane and carriage will move along the rails 5 and 6. As soon as the electromagnet 27 is de-energized, further movement will be prevented through the fact that the gears 19 and 39 will become disengaged.

Should it be desired to move the carriage in the opposite direction, the same action would take place with the exception 125 that the electromagnet 26 will be energized which will move the yoke in the opposite direction, thus engaging gears 18 and 39. Assuming now that the crane and carriage has been moved to a desired point and that 130

the operator wishes to swing the crane to one side, he presses a button which energizes the electromagnet 134. This immediately attracts the armature 133 with the result that the gear 89 is moved into engagement with the gear 87. This gear 87 is being rotated by the motor 78 with the result that the shaft 124 will be rotated in one direction. This will make the gear 126 carried upon the shaft 124 rotate about the turn table gear 41. Consequently the crane platform and crane structure will be swung to one side. If it is desired to swing the crane to the opposite side, the electromagnet 136 is energized which will move the gear 88 into engagement with the gear 87 and consequently the shaft 124 and its gear 126 will be rotated in the opposite direction.

Assuming now that the crane has been 20 swung to one side and it is desired to manipulate the hoisting cable 122, as it is first necessary to drop the hoisting cable so that the end may be engaged, the same is accomplished by pressing the button controlling 25 electromagnet 114. This pulls upwardly on the lever 111 which lever is in turn connected as at 117 to the brake band 118. This releases the hoisting drum 97 and consequently the cable 122 may be paid out as desired.

Assuming that the load has been connected 30 to the cable and it is desired to hoist the same, the proper button is pressed which energizes the electromagnet 102. This electromagnet pulls upon the armature 101 carried upon the lever 99 which in turn causes 35 the yoke 98 to push the hoisting drum into engagement with the clutch 94. As this clutch is being constantly driven by the gear 92 the result will be that the hoisting drum 40 97 will revolve and wind up the cable thus lifting the load. At the same time the electromagnet 102 has moved the arm 106 so that the end 108 is bearing against the lever 45 109, which lever is connected to the brake operating lever 111 and consequently the brake is released during the hoisting period. As soon as the current is turned off from the 50 electromagnet 102 the hoisting operation will cease and the brake will immediately be applied so that the load will be held where desired and cannot again be lowered until the electromagnet 114 is again energized.

It will thus be seen that I have produced 55 a device which will accomplish all the objects above set forth.

It is to be understood that the form of my 60 invention herewith shown and described is to be taken as a preferred example of the same and that various changes relative to the material, size, shape and arrangement of parts may be resorted to without departing from the spirit of the invention or the 65 scope of the subjoined claim.

Having thus described my invention, I claim:—

A remote control means for actuating mechanism positioned upon a movable carriage and adapted to move over tracks, of a plurality of conductors positioned between 70 said tracks, a plurality of contact fingers carried on said carriage and engaging said conductors, a rotatable platform positioned on said carriage, a motor positioned on said 75 rotatable platform, means for conducting current from one of said conductors to said motor, and a plurality of magnets positioned on said platform for the purpose of connecting said motor to apparatus mounted on 80 said platform, each of said magnets being electrically connected to one of said conductors whereby said magnets may be actuated from a remote point.

In testimony whereof I affix my signature. 85
DEAN S. MORROW.
